UNITED STATES PATENT OFFICE

ERNEST H. PEABODY, OF PELHAM MANOR, NEW YORK, ASSIGNOR TO PEABODY ENGINEERING CORPORATION, OF NEW YORK, N. Y., A CORPORATION OF NEW YORK

COMBINATION GAS AND OIL BURNER

Application filed February 28, 1925. Serial No. 12,302.

My invention relates to combination gas and oil burners, especially to that type for burning combustible gases, and liquids, more fully described in an application filed by me ⁵ simultaneously herewith, Serial Number 12,301, filed February 28, 1925 and has for its object to provide a means for mounting the air register and atomizer so that the gas chamber is more easily accessible.

10 A further object is to provide a simple means for supplying air through the gas burner, while burning liquid combustibles, in sufficient quantity to prevent warping and distortion of the gas burner.

15 The foregoing and other features of my invention will now be described in connection with the accompanying drawing forming part of this specification in which I have represented my device in its preferred form, ²⁰ after which I shall point out in the claims those features which I believe to be new and of my own invention.

In the drawings:—

Figure 1 is a side elevation of my device ²⁵ attached to a furnace front.

Figure 2 is a front view, with the details of the various connections omitted.

Figure 3 is a section 3—3, Figure 2.

Figure 4 is an enlarged cross sectional de- ³⁰ tail of the gas chamber showing the connection to outer air.

In the carrying out of my invention I employ an air register 1, adapted to support a standard atomizer 2, a gas chamber 3 provided with a circumferential slot 4 adapted to supply gas to a combustion chamber 5. The gas chamber is adapted to fit an opening 6 in a furnace front 7 and be secured thereto by means of stud bolts 8. The gas chamber is composed of two parts (10 and 13) forming an annular chamber provided with a gas inlet and circumferential slot 4 leading into the combustion chamber, all of which is more fully described in the application above referred to.

The part 10 of the gas chamber is fastened to the furnace front and the part 13 is secured to the part 10 by the bolts 16.

50 The part 10 is provided with openings 17 which are closed by the plugs 18 when gas

is burned and may be opened to provide means for cleaning. The removal of the plugs 18 would also permit air to enter the gas chamber 3 under the influence of the draft and flow through the gas chamber, ⁵⁵ finding its exit through the circumferential slot 4 during the time that oil is being used for fuel. In this way the parts forming the gas chamber will be cooled by the air and prevented from being distorted by reason of ⁶⁰ being too highly heated.

The part 13 of the gas chamber is provided with a seat 20 adapted to receive and center the male member 21 of the air register 1.

65 The air register is of any well known type provided with segmental doors 22 pivotally mounted at 23. The front plate 24 of the air register is provided with extensions 27, carrying means 28 for pivoting the door to ⁷⁰ the bracket or support 29 which may be bolted either to the gas ring 10 by means of bolts 8 or to the furnace front or both, as shown, to permit the air register to swing away from its seat formed in the wall of ⁷⁵ the gas chamber.

With this arrangement the air register may be swung away from the gas chamber permitting easy access to all operating parts. When the air register is swung towards the furnace front the part 21 contacts with the circular seat 20 of the gas chamber and thereby centers the unit in operating position.

80 In the foregoing disclosure I have described and illustrated my apparatus as designed for an enclosed housing surrounding the air register into which air for combustion is delivered under pressure but it may be adapted for use with a furnace where natural draft is employed and which therefore requires no housing as will be readily understood.

95 I wish it distinctly understood that my combination gas and oil burner herein described and illustrated is in the form in which I desire to construct it and that changes or variations may be made as may be convenient or desirable without departing from the salient features of my invention and ¹⁰⁰

I therefore intend the following claims to cover such modifications as naturally fall within the lines of invention.

I claim:

1. A burner comprising a fuel chamber adapted to fit an opening in a furnace wall, means for supplying fuel to said chamber and for discharging it therefrom, said chamber having a seat and an air register mounted to move to and from said seat.
- 10 2. A burner comprising a fuel chamber adapted to fit an opening in a furnace wall, means for supplying fuel to said chamber and for discharging it therefrom, said chamber having a seat, and an air register hinged to said chamber to swing to and from said seat.
- 15 3. A burner comprising a fuel chamber adapted to fit an opening in a furnace wall, means for supplying fuel to said chamber and for discharging it therefrom, said chamber having a seat, an air register mounted to move to and from said seat, and a liquid fuel atomizer carried by said air register.
- 20 4. A burner comprising a fuel chamber adapted to fit an opening in a furnace wall, means for supplying fuel to said chamber and for discharging it therefrom, said chamber having a seat, an air register mounted to move to and from said seat, and a liquid fuel atomizer carried by said register and mounted to discharge its fuel adjacent said chamber when in operation.
- 25 5. A burner comprising a fuel chamber adapted to be fitted to a furnace wall adjacent an opening therein, said chamber having a circumferential outlet, an air register mounted to move to and from a seat upon said chamber, and a liquid fuel atomizer carried by said air register and mounted to discharge its fuel adjacent said chamber when in operation.
- 30

- 40

In testimony whereof I affix my signature.
ERNEST H. PEABODY.
